CLAIM

The ornamental design for a fan wheel, as shown and described.

DESCRIPTION

FIG. 1 is a front view of a fan wheel according to the present invention;

FIG. 2 is a rear view of a fan wheel according to the present invention;

FIG. 3 is a side view of a fan wheel according to the present invention;

FIG. 4 is a rear perspective view of a fan wheel according to the present invention; and,

FIG. 5 is a front perspective view of a fan wheel according to the present invention.

The broken lines illustrate portions of the fan wheel that form no part of the claimed design.
